MANIFOLDING APPARATUS AND METHOD

Albert W. Metzner, Dayton, Ohio, assignor to The Standard Register Company, Dayton, Ohio, a corporation of Ohio

Application May 28, 1942, Serial No. 444,858

24 Claims. (Cl. 282—11.5)

This invention pertains to the manifolding art wherein superposed continuous record strips are progressively advanced past a recording position, and more particularly to means and method for automatically interchanging fresh carbon or transfer material interleaved between the record strips for exhausted sheets thereof in timed sequence with advancement of the record material.

Carbon or transfer material, however good the quality, wears out after a number of repetitive recordings long before an entire supply packet of record material is exhausted. One effort heretofore to obviate the difficulty was by use of continuous strips of "one time" carbon interleaved between the record strips and advanced in unison therewith. Such method wherein each area of the transfer material afforded but a single writing and was then discarded was extremely wasteful and expensive, even though a comparatively poor quality of carbon material was employed. The carbonized surface of the interleaved transfer material, even of poor quality, is capable of at least limited repetitive use in production of plural record impressions from one transfer area.

In autographic registers and imprinting apparatus it has not been uncommon to advance interleaved carbon transversely of the record strips little by little, either manually or automatically by the differential advancement of the record strips.

Otherwise the interleaved carbon material must be manually changed periodically to provide fresh transfer surfaces.

In the present instance a succession of individual sheets of transfer material are interleaved at longitudinally spaced intervals between the superposed record strips and as the record strips are progressively advanced past the recording position a set of superposed transfer sheets are temporarily arrested in the recording position until a predetermined number of sets of record forms have been advanced therebeyond, and the arrested strips have been repetitiously used until approximately exhausted whereupon the arrested set of transfer sheets is automatically released and discharged from the recording apparatus and is replaced by a fresh set of transfer sheets which in turn are arrested at the writing position.

The object of the invention is to improve the means and method of making manifold copies of records, and provide apparatus for automatically interchanging fresh transfer material for worn and exhausted material which is not only simple in construction and capable of being eco-

nomicly constructed, but which will be efficient in use, automatic in operation, uniform in action, having minimum operating parts and be unlikely to get out of repair.

5 A further object is to provide a method of automatically interchanging fresh carbon or transfer sheets for used and exhausted sheets periodically without special attention of the operator.

A further object of the invention is to provide 10 means for temporarily arresting carbon or transfer sheets interleaved between intermittently advanced continuous record strips at a recording position, and thereafter automatically releasing the arrested transfer material for replacement 15 with fresh material.

A further object of the invention is to provide a recording apparatus equipped with automatic transfer material interchanging devices.

20 A further object of the invention is to provide a recording apparatus embodying an automatic transfer material interchange mechanism possessing the advantageous structural features and meritorious characteristics and mode of operation herein mentioned.

25 The assembly of record strips and interspersed transfer sheets for use with an automatic transfer interchange apparatus as herein described forms the subject matter of a separate application 30 for patent Serial No. 444,857 filed concurrently herewith.

With the above primary and other incidental objects in view as will more fully appear in the specification, the invention intended to be protected by Letters Patent consists of the features 35 of construction, the parts and combinations thereof, and the mode of operation, or their equivalents, as hereinafter described or illustrated in the accompanying drawings.

40 In the drawings, wherein is shown the preferred but obviously not necessarily the only form of embodiment of the invention,

Fig. 1 is a longitudinal sectional view of a conventional type of autographic register to which 45 the present invention has been applied.

Fig. 2 is a top plan view thereof.

Fig. 3 is a transverse sectional view of the autographic register showing the relation of the transfer material arresting means.

50 Fig. 4 is a plan view of a portion of a manifolding assembly of record strips and interleaved longitudinally spaced transfer sheets for use in a recording apparatus equipped with transfer sheet arresting and interchange devices.

55 Fig. 5 is a perspective view illustrating the rela-

tion of successive sets of transfer sheets at the moment of interchange.

Like parts are indicated by similar characters of reference throughout the several views.

While for illustrative purposes the transfer material interchange devices and mode of operation have been shown and described in relation with a conventional type of autographic register, it is to be understood that it is not limited thereto, but in suitable size and proportion may be readily adapted to other writing and imprinting apparatus.

Referring to the drawings, 1 indicates an autographic register cabinet having therein a supply compartment 2 to receive a packet 3 of continuous series connected detachable form stationery, and a storage compartment 4 for at least a part of the inscribed portions of the record strips, the remainder of which are torn off as they are ejected from the register.

The superposed record strips 5, in the present instance are marginally punched at 6 for engagement of revoluble pin wheels 7 by which the strips are drawn from the supply compartment 2 over a writing tablet 8 into recording position, upon rotation of the pin wheels 7 by the hand crank 9 or by an actuating motor.

The present invention is not in any way dependent upon pin type feeding means or marginally punched holes in the strips and may be applied to recording apparatus having other types of strip feeding means.

Projecting through the writing tablet 8 at opposite sides of the path of travel of the record strips are yielding spring tensioned detent fingers 10 which are positioned to arrest advancing transfer material sheets in the writing position, until the traction influence thereon becomes sufficient to overcome the tension of the detent finger springs 11, which upon yielding release the arrested transfer material. The addition of the yielding fingers 10 and springs 11 is the only change or addition to a conventional autographic register which is necessary to accommodate the present automatic transfer interchange operation.

The manifolding assembly which includes the interchangeable transfer material comprises a plurality of superposed record strips 5 which are divisible at spaced intervals upon transverse weakened lines 12 into sets of individual sheets.

Distributed at spaced intervals throughout the length of the record strips are corresponding sets of transfer sheets 13 interleaved between the record strips. The relative spacing of the transfer material sets is somewhat dependent upon the quality of the material, or the number of copies which may be made therefrom before the transfer surface is exhausted. Ordinarily commercial transfer material has a capacity of thirty to fifty writings. Assuming that the estimated capacity is forty transfer records, the sets of transfer sheets 13 will be interleaved between every fortieth set of separable record sheets comprising the superposed strips.

However, the distribution of the record material may be at greater or less intervals which are preferably but not necessarily of equal extent.

Each transfer sheet 13 is provided at its trailing margin with an attached transverse anchor strip 14 of thin, relatively stiff material. This may be a paper binder or a cardboard strip the ends of which project laterally beyond the side margins of the record strips 5.

The projecting ends of the anchor strips 14 are preferably notched or shouldered to facilitate location of the transfer sheets during manufacture of the manifolding assembly, and for locating engagement with the detent fingers 10 of the recording apparatus.

The leading ends of the transfer sheets are securely attached to the accompanying strips 5 of record material. The record material sheets 13 are preferably stapled to the over and underlying record strips by wire staples 15 positioned quite closely to the leading margins of the transfer sheets. To enable the record strips to be relatively adjusted in unison with their advancement by the pin wheels 7, to insure proper registry of printed matter thereon, the staple 15 loosely holds the assembly together with freedom for limited movement vertically and longitudinally as is described in the copending application for Letters Patent Serial No. 395,629 of Urban M. Falter, filed May 28, 1941. However, other means of interconnection may be employed and such loose staple attachment is not essential to the present disclosure.

The record strips are of greater tensile strength than the transfer sheets and as the strips are advanced by the pin wheels 7, or other strip feeding means, the transfer sheets are advanced in unison thereby, with minimum tension or strain, until the projecting ends of the anchor strips 14 engage the detent fingers 10.

The interengagement of the projecting ends of the anchor strips 14 with the detent fingers 10 arrests the advancement of the particular set 35 of transfer sheets 13. The tensile strength of the transfer material being less than the tension of the springs 11 of the detent fingers the latter will resist further advancement of the transfer material sheets. The continuing advancement of 40 the record strips 5, the tensile strength of which is greater than that of the transfer material, will tear the staple 15 from the edges of the arrested transfer sheets, leaving the latter temporarily at rest in the recording position.

45 The arrested set of transfer sheets remains stationary, being held by the detent fingers 10, while the record strips 5 continue to be intermittently advanced past the recording position and relative to the arrested set of transfer sheets. The arrested set of transfer sheets are repeatedly used 50 to make record impressions upon succeeding sets of record portions of the strips, until the transfer surfaces of the arrested sheets are exhausted.

With each advancement of the record strips 55 to present successive sets of record receiving areas thereof in registry with the arrested transfer sheets, the next succeeding set of transfer sheets is also advanced through step by step movement toward the arrested set thereof.

As the set of transfer sheets thus advancing with the record strips approaches the recording position, the staple 15 thereof engages the anchor strips 14 of the arrested set of transfer sheets then in record making position and which 60 by such time have been substantially worn out or exhausted. The record strips being of greater tensile strength than the detent finger springs 11, the thrust of the staple 15 of the advancing set of transfer sheets under influence of further advance of the record strips 5, against the anchor bars 14 of the arrested set of sheets overcomes the yielding resistance of the detent fingers 10. The detent fingers yield against the tension of their springs to permit the ends of 65 the anchor bars 14 of the exhausted set of trans-

fer sheets to pass therebeyond and so frees the set of worn out transfer sheets, which then continue out of the register in unison with further advancement of the record strips. The detent fingers are returned by their springs to upright position to engage the ends of the anchor bars 14 of the advancing set of fresh transfer sheets.

However, as before stated the tensile strength of the transfer material being less than the resistance of the detent finger springs, when the advancement of the new set of transfer sheets is arrested by the detent fingers, the continued movement of the record strips causes the staple 15 to tear out of the leading margins of the transfer material leaving the substitute set of transfer sheets at rest in recording position, until released and displaced by a subsequent set thereof.

The sets of transfer material are detachably secured at spaced intervals to the record strips. Each set of transfer sheets is in turn caught by the detent fingers 10 in recording position, and is automatically detached from the conveyor strips by tearing strain upon the transfer material. It is so held until the succeeding set of transfer sheets is advanced to the interchange position. Thereupon then exhausted set of sheets is pushed ahead by the tractive power of the record strips which overcomes the yielding resistance of the detent fingers until the exhausted set of sheets is released thereby. The oncoming set of fresh transfer sheets is then arrested in like manner by the detent fingers and so held temporarily in completion of the cycle.

Thus at each cycle of operation a set of fresh transfer sheets interleaved between the record strip is interchanged for an exhausted set of transfer sheets also interleaved between the record strips at the end of a predetermined sequence of writing operations upon the record strips which will have been advanced independently of the positioned transfer strips through a predetermined travel range.

The fact that the transfer sheets are interfolded with the record strips while in the pack, and the travel distance from the pack to the recording position is relatively short, it is unlikely that the transfer sheets or their anchor strips will become laterally displaced or shifted into askew relation. However, as a precaution to guard against such displacement, upstanding guide flanges 16 are provided in parallel relation with the path of travel of the record strips. The guide flanges are so spaced as to permit free movement of the anchor strips 14 therebetween. The forward ends of the guide flanges 16 are slightly flared at 16' to deflect the ends of the anchor strips 14 inwardly in event of lateral displacement.

In the event that pin type feeding means is employed, the point of engagement is so located that at the end of the feeding movement by which exhausted transfer material is pushed from recording position, the feed pins will come to rest behind the anchor strip 14 of the displaced transfer sheet. This entirely frees the displaced transfer material which may then be immediately removed. Otherwise, the ends of the anchor strip 14 might be held by the feeding pins until the succeeding operation. However, it is to be understood that pin type feeding devices are not essential, and the invention is not dependent thereon. Frictional or other feeding means may be substituted therefor.

From the above description it will be apparent that there is thus provided a device of the char-

acter described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. The combination with a manifolding assembly comprising a plurality of superposed continuous record strips and a succession of sets of transfer sheets interleaved between the record strips at longitudinally spaced intervals, including lateral extensions on the transfer sheets projecting beyond the margins of the record strips, of a recording apparatus including strip feeding mechanism for advancing the record strips through a predetermined path in unison past a recording position and simultaneously advancing succeeding sets of transfer sheets into the recording position and a detent device adjacent the path of travel of the record strips by which the lateral extensions of succeeding sets of transfer sheets are engaged and temporarily arrested in recording position, and means operative by the continued advancement of the record strips for release of an engaged set of transfer sheets for replacement by a succeeding set thereof.
2. The combination with a manifolding assembly comprising a plurality of superposed continuous record strips and a plurality of longitudinally spaced sets of transfer sheets interleaved therebetween, of a recording apparatus including strip feeding means for progressively advancing the record strips past a recording position, detent means engageable with successive sets of transfer sheets for temporarily arresting the set of transfer sheets in recording position relative to which the strips continue to advance and release means operative by continued advancement of the record strips for disengaging the detent means and arrested set of transfer sheets to enable further advancement of the previously engaged set of transfer sheets preparatory to engagement and arrest of a succeeding set of such sheets in recording position.
3. The combination with a manifolding assembly comprising a plurality of superposed continuous record strips and a series of sets of transfer sheets interleaved between the strips at longitudinally spaced intervals, of an autographic register including a strip feeding device, a writing tablet over which the strips are collectively advanced past a recording position, a pair of spring tensioned depressible detent fingers projecting above the writing tablet at opposite sides of the path of travel of the strips, retracting springs for said fingers, extensions of the transfer sheets engageable with the depressible detent fingers to arrest successive sets of transfer sheets in recording position, and means operative incident to advancement of the strips for depressing the detent fingers to release the

engaged set of transfer sheets preparatory to engagement of a succeeding set of transfer sheets thereby.

4. An autographic register, including strip feeding devices and a writing tablet over which continuous strips of record material are progressively advanced, and a depressible detent located in laterally offset relation with the path of travel of the record strips over the writing tablet and temporarily engageable independently of the record strips with successive sets of transfer sheets interleaved at longitudinally spaced intervals between the record strips, and actuating means associated with each succeeding set of transfer sheets effective to depress said detent incident to advancement of the strips of record material to release an engaged set of transfer sheets preparatory to engagement and arrest of the succeeding set thereof of the longitudinally spaced series.

5. An autographic register, including strip feeding devices and a writing tablet over which a plurality of superposed continuous strips of record material are progressively advanced past a recording position by the feeding devices, detent means temporarily engageable with successive sets of transfer sheets interleaved at longitudinally spaced intervals between the record strips independently of the record strips to arrest such sets of transfer sheets in recording position and means associated with each succeeding set of transfer sheets for automatically disengaging the preceding arrested set of transfer sheets from the detent incident to advancement of the record strips preparatory to engagement and arrest of a succeeding set of transfer sheets thereby.

6. A recording apparatus including strip feeding devices for progressively advancing a plurality of superposed record strips past a recording position and a detent for temporarily arresting in recording position successive sets of transfer sheets interleaved at longitudinally spaced intervals between the record strips, and release means carried by the strips operative upon advancement of the record strips a predetermined distance to disengage the detent and transfer sheets preparatory to engagement and arrest of a succeeding set of such sheets by the detent.

7. A recording apparatus wherein a manifolding assembly comprising sets of interleaved transfer sheets of lesser tensile strength are connected at longitudinally spaced intervals to continuous record strips of greater tensile strength is advanced past a recording position, including strip feeding devices for advancing the record strips, and a yielding detent engageable with succeeding sets of interleaved transfer sheets independently of the record strips for temporarily arresting the sets of transfer sheets in the recording position, the resistance of the yielding detent means being greater than the tensile strength of the transfer material, whereby the arrested transfer material will be detached from the record strips by the pulling influence of continued advancement of the latter, the resistance of the yielding detent being less than the tensile strength of the record strips, whereby said detent may be overcome by the pulling influence of the record strips to release the arrested set of transfer sheets preparatory to replacement thereof by a succeeding set of such sheets.

8. A recording apparatus, wherein a manifolding assembly of sets of transfer sheets of lesser tensile strength interleaved at longitudinally

spaced intervals between superposed continuous record strips of greater tensile strength is progressively advanced past a recording position, including strip feeding means having operative

5 engagement with at least one of the record strips, a releasable arresting device engageable with succeeding sets of interleaved transfer material independently of the record strips for temporarily arresting the sets of transfer material
10 one by one in recording position, and tensioning means for the arresting device, the resistance of which is greater than the tensile strength of the transfer material and less than that of the record strips, the construction and arrangement being such that the resistance of the arrested transfer material when engaged by the arresting device is overcome by the pulling influence of the record strips and the resistance of the arresting device is subsequently overcome by
15 further pulling influence of the record strips to release the arrested set of transfer sheets preparatory to arrest of a succeeding set thereof.

9. A recording apparatus, wherein a plurality of superposed continuous strips of record material are collectively advanced past a recording position, including strip feeding devices and an arresting detent temporarily engageable independently of the record strips with succeeding sets of transfer sheets interleaved at longitudinally spaced intervals between the record strips for arresting the set of transfer sheets in recording position, and release means therefor periodically operative to automatically release an engaged set of transfer sheets preparatory to engagement and arrest of a succeeding set thereof.

10. The herein described method of automatically interchanging fresh transfer sheets for exhausted transfer sheets interleaved between continuous superposed record strips including interleaving successive sets of transfer sheets at longitudinally spaced intervals between superposed continuous record strips, advancing the strips and interleaved transfer sheets past a recording position, arresting a set of interleaved transfer sheets in the recording position, continuing the advancement of the strips and a succeeding set of transfer sheets relative thereto, automatically releasing the arrested set of transfer sheets for continued advancement in unison with the record strips upon the approach of the succeeding set of interleaved transfer sheets to the recording position and arresting the succeeding set of interleaved transfer sheets
50 in the position vacated by the released set thereof.

11. The herein described method of interchanging sets of transfer sheets interleaved between superposed record strips, including interleaving succeeding sets of transfer sheets at longitudinally spaced intervals between superposed record strips and detachably engaging the sheets with the strips for unison advancement, advancing the strips past a recording position, arresting the advancement of a set of interleaved transfer sheets in recording position while continuing the advancement of the strips, the pulling strain of which effects detachment of the sheets from the strips, continuing the advancement of the strips until a succeeding set of transfer sheets approaches recording position, and reengaging the arrested set of transfer sheets with the record strips for unison advancement out of recording position preparatory to arrest of the approaching succeeding set of

transfer sheets in the position vacated by the previous set of transfer sheets.

12. The herein described method of interchanging fresh and worn transfer sheets interleaved between superposed record strips of a manifolding assembly, including interleaving succeeding sets of transfer sheets at longitudinally spaced intervals between superposed record strips, attaching the sets of transfer sheets and record strips by stapling the record strips and interleaved transfer sheets together, advancing the so constructed manifolding assembly relative to a recording position, arresting a set of interleaved transfer sheets in the recording position, disengaging the arrested set of sheets from the record strips by continuing the advancement of the strips and tearing the staple from the interleaved arrested transfer sheets, continuing the advancement of the record strips until a succeeding set of interleaved transfer sheets approach the recording position, and utilizing the attachment staple pertaining to such succeeding set of interleaved transfer sheets while continuing the advancement of the strips to push the preceding set of interleaved transfer sheets out of recording position preparatory to arrest of the succeeding set of transfer sheets in the position vacated by the preceding set thereof.

13. The herein described method of automatically interchanging fresh and used transfer material of a continuous manifolding assembly, including disposing succeeding sets of interleaved transfer sheets at longitudinally spaced intervals between superposed continuous record strips, advancing succeeding portions of the strips past a recording position, arresting a set of interleaved transfer sheets in recording position, continuing the advancement of the strips, and subsequently automatically pushing the arrested set of transfer sheets out of recording position by the advancement of a succeeding set thereof in unison with the advancement of the strips preparatory to arrest of the succeeding set of transfer sheets in the position vacated by the preceding set thereof.

14. The herein described method of automatically interchanging fresh and used transfer material of a continuous manifolding assembly, including arranging succeeding sets of interleaved transfer sheets between superposed record strips at longitudinally spaced intervals, advancing succeeding portions of the record strips and interleaved transfer sheets relative to a recording position, arresting a set of interleaved transfer sheets in the recording position, continuing the advancement of the strips relative to the arrested set of transfer sheets and by continued advancement of the record strips relative to the arrested transfer sheets subsequently automatically releasing and displacing the arrested transfer sheets from the recording position preparatory to arrest of a succeeding set of transfer sheets in the position vacated by the displaced transfer sheets, and continuing the described operation in repetitious sequence.

15. The herein described method of automatically interchanging fresh and used transfer material of a continuous manifolding assembly, including arranging succeeding sets of interleaved transfer material of lesser tensile strength at longitudinally spaced intervals between superposed continuous record strips of greater tensile strength, interconnecting the transfer sheets and record strips for unison travel movement, ad-

vancing the record strips past a recording position, arresting a set of interleaved transfer sheets in the recording position, detaching the transfer sheets from the strips by rupture of the transfer sheets under the pulling influence of the record strips of greater tensile strength, and subsequently displacing the arrested set of transfer sheets from recording position by advancement of a succeeding attached set of transfer sheets in unison with the further advancement of the record strips prior to their detachment from the strips, preparatory to replacement of the displaced set of transfer sheets by said succeeding set thereof.

16. A recording apparatus including strip feeding means for progressively advancing superposed continuous strips of record material past a recording position, a detent in proximate relation with the recording position and engageable with successive sets of transfer sheets interleaved between the record strips to arrest and temporarily hold the transfer sheets in recording position while the record strips are advanced relative thereto, and means associated with a succeeding set of transfer sheets being advanced in unison with the record strips for disengaging the arrested transfer sheets from the detent for movement out of recording position in unison with further movement of the record strips, said detent being reengageable with the said succeeding set of transfer sheets to temporarily arrest said succeeding set of transfer sheets in recording position until released in like manner.

17. A strip feeding apparatus wherein continuous superposed strips of record material having sets of transfer sheets interleaved therebetween at longitudinally spaced intervals is progressively advanced past a recording position, including a detent device for temporarily arresting one set of interleaved transfer sheets until a second set thereof approaches the record receiving position, and automatic release means associated with each succeeding set of transfer sheets operative to automatically effect release of the preceding arrested set of transfer sheets as each succeeding set of transfer sheets approaches recording position.

18. A recording apparatus wherein continuous superposed strips of record material having sets of transfer sheets interleaved therebetween at longitudinally spaced intervals is progressively advanced past a recording position, including a yieldable detent engageable with succeeding sets of transfer sheets independently of the record strips and having resistance greater than the tensile strength of the transfer material and less than that of the record strips, and operative against the tensile resistance of the transfer material to temporarily arrest each succeeding set thereof in recording position, and operative under tension influence of the record strips to release the arrested transfer sheets.

19. The herein described method of automatically interchanging fresh transfer material for used material of a manifolding assembly, including detachably interconnecting interleaved sheets of transfer material with superposed strips of record material at longitudinally spaced intervals for unison advancement relative to a recording position, detaching the transfer sheets from the record strips at the recording position, advancing the superposed record strips through a further range of movement independently of the transfer sheets, reengaging the previously de-

tached transfer sheet with the superposed record strips, advancing the strips and reengaged transfer sheet beyond the recording position and simultaneously advancing a succeeding transfer sheet into the recording position in a continuing sequence.

20. The herein described method of automatically interchanging fresh transfer material for used material of a manifolding assembly, including progressively advancing succeeding transfer sheets interleaved at longitudinally spaced intervals between superposed record strips in unison with the strips into a recording position, temporarily arresting each advanced transfer sheet in turn in said recording position while continuing to advance the record strips relative thereto, and thereafter continuing the advancement of the previously arrested transfer sheet beyond the recording position in unison with the further advancement of the record strips, and replacing the advanced transfer sheet with a succeeding transfer sheet advanced into recording position in unison with advancement of the record strips in a continuing sequence.

21. The herein described method of periodically interchanging fresh transfer sheet units for used transfer sheet units interleaved between superposed continuous record strips, including progressively advancing the strips and longitudinally spaced interleaved transfer sheets interleaved therebetween in unison from a source of supply to a recording position, temporarily arresting the advance transfer sheet unit in the recording position while continuing advancement of the strips and a succeeding transfer sheet unit relative thereto, and automatically pushing the arrested transfer sheet unit from the recording position by advancement of the succeeding transfer sheet unit into such position.

22. The herein described method of automatically interchanging fresh transfer sheet units and used transfer sheet units interleaved between superposed continuous record strips including alternately advancing the record strips relative to a recording position in unison with longitudinally spaced interleaved transfer sheet units, tem-

porarily arresting each interleaved transfer sheet unit in the recording position while the record strips are further advanced relative thereto, and utilizing the next succeeding transfer sheet unit being advanced in unison with the record strips to automatically displace the previously arrested transfer sheet unit from the recording position and arresting said next succeeding advanced transfer sheet unit in the position from which it displaced the preceding unit.

23. The herein described method of intermittently supplying fresh transfer material in a manifolding assembly, including interleaving sets of transfer sheets between continuous superposed strips of series connected printed form stationery at longitudinally spaced intervals, progressively advancing succeeding form lengths of the strips and a set of transfer sheets in unison until the transfer sheets arrive in recording position, temporarily arresting the set of transfer sheets in recording position, continuing the advance of the record strips relative thereto through a plurality of form lengths thereof and engaging the record strips with the arrested transfer sheets for further unison travel movement thereof out of the recording position.

24. The herein described method of interchanging fresh and used transfer sheets of a manifolding assembly, including the steps of interleaving 30 sheets of transfer material at longitudinally spaced intervals between superposed record strips, progressively advancing the record strips and succeeding spaced transfer sheets in unison, temporarily arresting the advancement of the transfer sheets in recording position while continuing the advancement of the record strips relative thereto until a succeeding transfer sheet has approached the recording position, utilizing the advancing record sheets for advancing the temporarily arrested sheet beyond recording position in unison with the record strips, and temporarily arresting the succeeding transfer sheet in the position vacated by the previously arrested and transfer sheet.

ALBERT W. METZNER.
